(57) **CLAIM**

The ornamental design for a motion-activated night light with swivel lens, as shown and described.

DESCRIPTION

FIG. 1 is a front, right side and bottom perspective view of a night light showing my new design;

FIG. 2 is a front elevational view thereof;

FIG. 3 is a left side elevational view thereof, the right side elevational view being a mirror image of FIG. 3;

FIG. 4 is a top plan view thereof;

FIG. 5 is a bottom elevational view thereof; and,

FIG. 6 is a rear elevational view thereof.

The portions of the motion-activated night light with swivel lens shown in broken lines form no part of the claimed design.

1 Claim, 5 Drawing Sheets
